BORE SAFETY DEVICE FOR TIME FUSES

Richard H. Whitehead, New Haven, Conn., assignor, by mesne assignments, to the United States of America

Application June 20, 1939, Serial No. 280,071

2 Claims. (Cl. 102—84)

1

This invention relates to a bore safety device for time fuses to prevent the possibility of the fuses from being detonated prior to their insertion in the gun and until they have been expelled from the gun.

Time fuses, as now manufactured, comprise generally a specialized type of clock train which is started in action at the time of firing and which have a time train adapted to be fired as soon as the clock mechanism releases the firing pin. The mechanism which restrains a movement of the firing pin until released by the timing mechanism is delicate, relative to the severe forces to which it is subjected, and on this account, particularly when manufactured under quantity production methods, rough handling or slight inaccuracies of manufacture make it possible that the firing pin shall be discharged prematurely as the forces from set back at time of firing are tremendous and might cause a premature firing.

It is an object of this invention to provide a mechanism within such a fuse which will absolutely prevent the detonation of the fuse until the fuse has actually left the gun.

The invention accordingly comprises an article of manufacture possessing the features, properties and the relation of elements which will be exemplified in the article hereinafter described and the scope of the application of which will be indicated in the claims.

For a fuller understanding of the nature and objects of the invention, reference should be had to the following detailed description, taken in connection with the accompanying drawing, in which:

Fig. 1 is a plan view of my improved mechanism as applied to a fuse. This figure being a section on the line 1—1 of Figure 2 through the fuse itself.

Fig. 2 is a side elevation of the fuse, parts being broken away to show the relationship of the invention in the fuse.

The invention being applicable to substantially any type of modern time fuse having a firing pin released by the timing mechanism; I have not deemed it necessary to include a description of any particular type of fuse construction. Sufficient to say that it comprises generally a frame 10 which may be composed of a plurality of superposed plates, if desired, and carrying a time train, not shown, driven by centrifugal weights 11 in response to the rotation of the fuse due to the rifling of the gun or by other driving means such as wound springs.

The time train is provided with some sort of setting mechanism not described, in accordance

with which after a predetermined time the fuse is detonated. This is accomplished as follows:

Mounted in the frame 10 is a firing pin 12 urged downwardly by a compressed helical spring 13 so that when unimpeded it may be forced to its lowermost position as shown in dotted lines at 14 to detonate the primer. The firing pin 12 is, however, provided with a shoulder 15 which is engaged by a lever member 16, the action of which is controlled by the time train. The connections between the time train and the lever 16 are not here described in detail because they form no part of this invention, it being sufficient to say that the firing pin is held in its cocked position by the lever 16 until the lever 16 is released or withdrawn by the time train. In general it is customary that the lever 16 shall be of such a nature that it is thrown out of position from beneath the shoulder 15 by centrifugal force and that it is held in position by the time train so that the force for throwing it out is dependent upon the rotation of the shell. Nevertheless, in some cases, particularly where the underside of the shoulder 15 is convex, the force of the spring itself may tend to throw the lever out even while the shell is stationary.

The foregoing parts comprise a part of the structure of a standard fuse.

In accordance with this invention there is provided transverse to the pathway of the firing pin a groove 17. In practical construction this may be provided by dividing the frame 10 into two portions by a separate plate 18 cut out as shown at 19 in Figure 1 to provide the clearance desired. Within this clearance there is mounted upon a pin 20 a dog 21 which is movable about the pin 20 from a position across the pathway of the firing pin 12, as shown in solid lines in Figure 1, to a position free from the pathway of the firing pin 12 as shown in dotted lines in Figure 1, being across the pathway in the inner position and away from the pathway in its outer position so that the normal centrifugal force due to the rotation of the shell in response to the rifling of the gun throws the dog to its outer position so that it no longer obstructs the movement of the firing pin.

A soft spring 22 bears against the dog 21 normally to assist in holding it in its inner position during the normal handling of the fuse, but the dog is provided with a recess 23 adapted to receive the end of the spring 22 to hold the dog in its outer position once it has been forced to that position.

The pin 24 is arranged to engage the dog 21 in

its outer position to limit the extent to which it can move outwardly.

With the construction here shown the fuse is adapted for rotation in the counterclockwise direction as shown by the arrow 25 in Figure 1 and it will be noted in Figure 1 that the pin 20 is in advance of the body of the dog 21 in the direction of rotation. This is an important factor in adding to the safety of the device.

The events which transpire in the firing of the propulsive charge of a large gun are not well understood and any statement based upon them is necessarily, therefore, clouded by that lack of definite knowledge. These time fuses, are, for example, for naval operations, intended for use in five inch guns and in such a gun that shell during its travel through the bore of the gun starts from rest and is brought to a speed of over 12,000 revolutions a minute in perhaps less than .01 of a second. During this period, acceleration forces are very strong and may be in excess of the centrifugal forces and this fact is utilized to help keep the bore safety closed. As will be seen from Figure 1, the attempt rapidly to accelerate the structure of Figure 1 in a counterclockwise direction will tend to make the pin 20 drag the dog 21 directly behind it and this is the period when the maximum protection is required while the projectile is in the bore of the gun. As soon, however, as the rotation of the shell becomes more uniform in its rate and attains its maximum velocity and the acceleration falls off the centrifugal forces resulting from the rotational velocity become dominant and these in turn are of great dimension because of the high speed of rotation. At this time the dog 21 is thrown violently outward out of the path of the firing pin.

From this construction two facts will be noted. (1) that the dog 21 is never in contact with the firing pin 12 unless there has been a premature release of the firing pin by a failure of the timing mechanism or by the set back forces. Thus there is no friction between the dog 21 and its cooperating parts which has any bearing upon the normal operation of the time fuse. It will also be noted that the dog 21 moves in substantial contact with the plates below and if it is struck by the firing pin it has the full support of that plate to resist the movement of the firing pin. The force of the firing pin is, however, considerable and if the dog is in the way it tends to imbed itself in the surface of the dog, thus if the pin be prematurely released by the firing mechanism the dog itself is held in position by the firing pin to prevent premature explosion.

It will thus be seen that this device, so long as the dog 21 is across the path of the firing pin, absolutely prevents any detonation by the firing pin no matter what the failure of the timing mechanism may be and that the dog 21 during the rest is held in this obstructive position by the spring 22, while in the bore of the gun there is brought into play the additional factor of the acceleration of the shell to prevent the movement of the dog 21 and this is not overcome until after the shell leaves the gun.

Since certain changes may be made in the above construction and different embodiments of the invention could be made without departing from the scope thereof, it is intended that all matter contained in the above description or shown in the accompanying drawing shall be interpreted as illustrative and not in a limiting sense.

It is also to be understood that the following claims are intended to cover all of the generic and specific features of the invention herein described, and all statements of the scope of the invention which, as a matter of language, might be said to fall therebetween.

Having described my invention what I claim as new and desire to secure by Letters Patent is:

1. In a time fuse having a timing mechanism, a firing pin mounted for movement parallel to its own longitudinal axis, means releasable by said timing mechanism to retain said pin in cocked position, means to move said pin when so released, a plate disposed transversely to said pin and apertured for passage thereof, and a dog pivoted at one end disposed to cover said aperture when in unarmed position and movable by centrifugal force to uncover said aperture, the pivotal point of said dog lying angularly in advance of said aperture in the direction of rotation of said fuse when in flight in a projectile, the center of gyration of said dog being so positioned with respect to the pivotal point of the dog that centrifugal force does not move said dog until acceleration has ceased, a leaf spring fixed at one end and having a free end bearing against the edge of said dog more remote from the center of said device to oppose fortuitous movement of said dog, there being in said edge of the dog, a cut-out portion in which said free end of the spring engages when said dog has been moved to uncover said aperture to lock said dog after being moved.
2. In a time fuse having a timing mechanism, a firing pin mounted for movement parallel to its own longitudinal axis, means releasable by said timing mechanism to retain said pin in cocked position, means to move said pin when so released, a plate disposed transversely to said pin and apertured for passage thereof, and a dog pivoted at one end disposed to cover said aperture when in unarmed position and movable by centrifugal force to uncover said aperture, the pivotal point of said dog lying angularly in advance of said aperture in the direction of rotation of said fuse when in flight in a projectile, the center of gyration of said dog being so positioned with respect to the pivotal point of the dog that centrifugal force does not move said dog until acceleration has ceased, yieldable means bearing against that edge of the dog more remote from the center of said device to oppose fortuitous movement of the dog, said edge having a shoulder to engage said yieldable means when said dog has been moved to uncover said aperture to lock said dog after being moved.
